PYROLYTIC CONVERSION OF PARAFFINS
Joseph C. Krejci, Phillips, Tex., assignor to Phillips
Petroleum Company, a corporation of Delaware
Filed Sept. 21, 1959, Ser. No. 841,380
9 Claims. (Cl. 260—679)

This invention relates to the pyrolytic conversion of hydrocarbons containing substantial amounts of aliphatic unsaturated hydrocarbons. A specific aspect of the invention is concerned with the production of ethylene and acetylene.

The invention is an improvement in the process of my U.S. Patent 2,750,434, issued June 12, 1956. The process disclosed and claimed therein comprises pyrolyzing hydrocarbon feed stocks at temperatures in the range of about 1300 to 3500° F. by introducing a preheated hydrocarbon feed axially into a first cylindrical reaction zone of greater diameter than its length contiguous to and coaxial with a second cylindrical reaction zone of lesser diameter than the first zone and of greater length than diameter; injecting tangentially into the first reaction zone a combustible mixture of gaseous fuel and oxidant, such as O₂ or air; and burning the mixture to form hot combustion gases for heating the feed; passing the feed, initially surrounded by a helically moving annular blanket of said combustion gases, into the second reaction zone, whereby the feed is heated by the combustion gases to a temperature in the range of 1300 to 3500° F. to cause the same to react and form predominantly less saturated hydrocarbons; quenching the effluent from the second reaction zone in a quench zone to a temperature below reaction temperature; and recovering unsaturated hydrocarbons from the quenched effluent.

I have found that the incorporation of substantial proportions of steam in the hydrocarbon feed in the preheating zone has the multiple advantages of increasing the concentration and yield of unsaturates, particularly, acetylene and ethylene, in the effluent from the second reaction zone of the reactor, decreasing the carbon deposition in the reactor, and also decreasing the carbon deposition in the quench zone downstream of the second reaction system. It might be expected that the introduction of steam to the precracking furnace would decrease coking therein; however, it was not expected that this introduction of steam would have the beneficial effect of also decreasing the coke deposition in the reactor and in the quench chamber adjacent the effluent end of the second reaction zone.

Accordingly, it is an object of the invention to provide an improved process for pyrolytically converting hydrocarbon feed stocks containing paraffins to less saturated hydrocarbons with increased yield of unsaturates and higher concentrations thereof in the reaction effluent. Another object is to provide a pyrolytic process for converting hydrocarbon feed stocks to less saturated products with less formation of coke in the reaction system and particularly in the reactor and in the quench chamber adjacent the effluent end of the reaction system. Another object is to reduce coking in a precracking furnace and increase the unsaturates produced therein. Other objects of the invention will become apparent upon consideration of the accompanying disclosure.

The invention comprises incorporating in the feed to the precracking furnace an amount of steam in the range of about 10 to 125 volume percent of the hydrocarbon feed and preheating the mixture to a temperature in the range of 1000 to 1600° F. so as to crack and upgrade a substantial proportion of the hydrocarbon feed, and passing the precracked feed into a reactor of the character described and under the reaction conditions set forth in the aforesaid patent.

2

A more complete understanding of the invention may be had by reference to the accompanying schematic drawing of which FIGURE 1 is a transverse sectional view taken on the line 1—1 of FIGURE 2 and FIGURE 2 is a cross-sectional view of the furnace taken on the line 2—2 of FIGURE 1.

Referring to FIGURE 1, an elongated reaction zone 10 is lined with highly refractory material 12, such as corundum, silica, mullite, zirconia, or sillimanite brick, or other similar suitable materials resistant to high temperatures developed in the reactor. Upstream from and contiguous to reaction zone 10 is a combustion zone 14, axial with zone 10, also lined with refractory material 12. Lining 12 is surrounded by a layer of insulating material 16 and the whole is sheathed in a steel shell 18. Combustion chamber 14 should have a relatively large diameter in comparison to its length while the reverse is true of reaction chamber 10.

At the upstream or inlet end of combustion chamber 14, 20 a feed inlet tube 20 is arranged axially so that hydrocarbon feed introduced therethru passes axially thru both chambers 14 and 10. Surrounding a portion of feed conduit 20 is a coaxial larger conduit 22 for introducing oxygen or air to the axial feed when this is desired. The 25 arrangement of conduits 20 and 22 defines an annular space thru which oxygen or air may be passed into tube 20 thru holes therein (not shown) so that the fuel and air mixture may be passed axially into chamber 14. A cooling jacket 24 surrounds the inner end of injection tube 20 and is connected with an inlet water line 25 and an outlet water line 26. Water is circulated thru the jacket from line 25 along the length of the jacket and back to outlet line 26. This cooling of tube 20 lengthens its life.

35 FIGURE 2 shows combustion chamber 14 coaxial with reaction chamber 10 and provided with tangential ports or tunnels 28 spaced 180° apart. The outer end of the tunnel 30 is of smaller diameter than the inner portion. A feed inlet pipe 32 is surrounded by a water jacket 34 40 of the same or similar construction to jacket 24 provided with inlet and outlet lines 36 and 37, respectively. The inlet assembly is positioned so as to inject the feed thru tunnels 30 and 28 into combustion zone 14 where it is burned. Each tangential inlet conduit 32 is connected with an oxygen or air supply line 40 and a fuel gas supply line 42. Most of the tangentially introduced fuel gas is burned in tunnels 28 and chamber 14. Air line 44 and steam line 45 connect with line 46 leading into preheater 48 containing heating coils 50. Line 47 connects the outlet end of heating coil 50 with line 40 leading into feed injection conduit 32. In the event that the steam and air are to be introduced to the tangential burners without other preheating than that supplied by the steam, these gases may bypass preheater 48 thru line 52.

60 Returning to FIGURE 1, a cooling assembly 56 at the effluent end of reaction chamber 10, contiguous and coaxial therewith, comprises a water jacket 58, water spray 60, water inlet conduit 62 extending thru the jacket, a cooling water inlet 64, and a cooling water outlet 66 from jacket space 68. Effluent hot gases from the reactor are quenched in cooling assembly 56 to below reaction temperature and the quenched gases are passed via conduit 70 to conventional separation means 72 where acetylene is removed thru line 74, ethylene thru line 76, other olefins thru line 78, aromatics thru line 80, byproduct paraffins thru line 82, heavy residual materials thru line 84, and water thru line 86.

65 The axial feed comprising steam and paraffin-containing hydrocarbon material introduced thru lines 88 and 89, respectively, are introduced to pre-cracking furnace 90 thru line 91 where the hydrocarbon feed is subjected

to cracking in tube coil 92. The partially cracked hot effluent is passed thru line 93 into feed injection tube 20 for injection axially thru combustion chamber 14 into reaction chamber 10.

In the event oxygen is injected with the axial feed, this gas may be introduced thru line 94 to preheater 95 and thence into line 96, or it may bypass heater 95 and pass thru line 97 into line 96.

Operation in accordance with the invention comprises injecting a mixture of natural gas (or other fuel gas) and air or oxygen wherein the amount of oxygen is in the range of 50 to 140 percent and, preferably, 90 to 120 percent of theoretical for complete combustion, is preferably pre-heated and charged to the tangential burners through burner tubes 32 to provide tunnel temperatures up to 3500° F. and sufficient to heat the axial feed to the desired temperature. It is preferred not to heat the air or oxygen in admixture with the fuel gas because of the explosion hazard. The oxygen supply may be heated in admixture with steam, in the event steam is utilized in the tangential feed.

The axial feed comprising hydrocarbon and steam is preheated in heater or tube cracker 90 to convert paraffins to unsaturates before introducing the hot effluent from line 93 into injection tube 20. The steam admixed with the feed should be in the range of 10 to 125 volume percent of the hydrocarbon. It is preferred to maintain the steam in the axial feed in the range of 25 to 100 volume percent of the hydrocarbon. This feed is heated preferably to a temperature in the range of 800 to 1600° F. so as to crack and upgrade a substantial proportion of the hydrocarbon in the feed. While axial hydrocarbon feed may contain unsaturates, it is preferred to utilize aliphatic paraffins because of their relative cheapness. It is recognized that unsaturates convert more readily to ethylene and acetylene, but the cost of these hydrocarbons is substantially greater than the cost of corresponding paraffins. Suitable paraffins include methane, ethane, propane, butane, pentane, hexane and other available hydrocarbon stocks containing substantial amounts of these paraffins such as naphtha, kerosene, and gas oils. The paraffins may be introduced singly in high concentration or in admixture with each other or with unsaturates.

The axial feed cracked by heating to a temperature in the range of 1000-1600° F., and preferably in the range of 1400 to 1600° F., containing a substantial proportion of unsaturates due to the precracking, enters combustion zone 14 surrounded by spiralling combustion gas therein and passes into reaction chamber 10 surrounded by a blanket of spiralling combustion gas adjacent the refractory wall 12. In passing through reaction zone 10, the axial feed is heated to the desired range to produce the desired acetylene and/or ethylene and the effluent is quenched in quenching means 56 by the water injected

through spray 60 and by water circulating through jacket 58. The effluent from chamber 10 is quenched to a temperature below reaction temperature which is generally below 800° F. The quenched effluent is then passed through line 70 into conventional product separation means 72 from which the various constituents are separated in known manner and recovered as desired.

The quantities and rates of flow of the tangential and axial feeds are regulated to produce the optimum temperatures and reaction times for any particular feed to produce the optimum or maximum amounts of the desired products. Reaction time is very short in order to avoid overcracking and decomposition to carbon and hydrogen and is usually in the range of 0.5 to 0.001 second and even less. The reaction time depends upon the feed, the temperature in the reaction zone, and the product desired. Reaction time may be calculated in accordance with the equations set forth in my U.S. Patent 2,750,434, referred to supra.

20 When steam is included in the tangential feed, the volume ratio of steam to O_2 is in the range of 1:1 to 8:1 and it is preferred to preheat the steam — O_2 mixture to the range of 800 to 1600° F.

The advantages of the invention are illustrated by the following examples which are to be considered illustrative and are not to be construed to unduly limit the invention.

EXAMPLE I

30 Butane was pyrolytically converted to acetylene in substantial yield in a 3 inch tangential reactor at atmospheric pressure. The reactor was constructed in accordance with the drawing, precombustion chamber 14 being 11 inches in diameter and 4 inches long, while chamber 10 was 25 inches in length and 3 inches in diameter. Natural gas was used for the tangential fuel because of its availability and cheapness. A number of runs under different conditions were made and four of these runs which are typical are presented in Table I below.

The axial feed was preheated and cracked by being passed through a tube furnace prior to introduction to the reactor. In run 1, no steam was included in the axial feed. In run 2 the effect of mixing 25 volume percent steam with the butane may be seen. There was an increased concentration of the acetylene in the effluent and a substantial reduction in coking in the quencher. The duration of the run at equilibrium conditions was about 8 hours in each instance. In run 3 the volume of steam was doubled but there was no significant improvement in results. However, this run was of only 8 hours' duration and it is possible that over longer periods of operation, higher steam concentration may result in further reduction in coking in the quencher. In run 4 steam was included in the tangential feed and this feed was preheated to 1015° F. The acetylene concentration was slightly higher than without air preheat and the yield was slightly lower.

Table I

Run No.	Axial			Tangential					Reactor pressure p.s.i.a.	Olefin conc. preheat effluent, vol. percent	Butane destroyed in preheater
	Butane rate, lb./hr.	Steam, percent based on butane	Feed preheat, ° F.	Gas rate, c.f.h.	Air rate, c.f.h.	Steam rate, c.f.h.	Steam and air preheat, ° F.	Tunnel temperature, ° F.			
1.....	83.2	—	1,425	680	7,470	—	—	—	—	41.8	58.8
2.....	83.0	25	1,450	680	7,470	—	—	—	—	44.4	64.4
3.....	92.0	50	1,455	680	7,470	—	—	—	—	44.1	63.0

5
EXAMPLE II

Runs were made to convert propane to acetylene and ethylene in the reactor of Example I, again using natural gas and air as the tangential fuel. The data representing typical runs are set forth in Table II as runs 5, 6 and 7. The composition of the propane feed utilized in the runs is as follows.

Run 5:	Percent
C ₃ H ₈	67.8
C ₂ H ₆	0.3
iC ₄ H ₁₀	18.7
nC ₄ H ₁₀	13.2

Run 6:	Percent
C ₃ H ₈	92.3
C ₂ H ₆	2.6
iC ₄ H ₁₀	3.4
nC ₄ H ₁₀	1.4

Run 7:	Percent
C ₃ H ₈	96.3
C ₂ H ₆	3.4
iC ₄ H ₁₀	0.2
nC ₄ H ₁₀	0.1

The runs show that results obtained from different concentration of propane in the feed are not materially different. The propane feed rates were varied in the different runs with higher rates showing higher ethylene yields. The yield of acetylene plus ethylene was as high as about 54 percent. In runs 5 and 6 there was no carbon deposition in the reactor and greatly reduced carbon deposition in the quencher compared with runs without steam in the axial feed. In run 7 there were a few small specks of carbon deposit in the reaction section 10.

Variations and modifications are possible within the scope of the disclosure and claims to this invention, the essence of which comprises precracking a hydrocarbon feed containing a substantial proportion of aliphatic paraffin, such as at least 50 volume percent, in admixture with at least 10 volume percent steam based upon the hydrocarbon feed so as to convert paraffins to olefins and, then, pyrolytically converting the resulting feed to unsaturates comprising acetylene and ethylene in a tangentially fired reactor, wherein the feed is heated and reacted within a helically moving annular blanket of combustion gases as it passes thru the reaction zone. The invention effects improved yields of ethylene and acetylene from relatively cheap paraffins and also decreases the carbon deposition in the reactor and in the quench chamber at the effluent end of the reactor.

I claim:

1. In a process wherein a hydrocarbon feed is pre-heated in a tube cracker and passed in vapor form axially into a first cylindrical reaction zone of greater diameter than its length, contiguous to and coaxial with a second cylindrical reaction zone of lesser diameter and greater length; a combustible mixture of gaseous fuel and oxidant are injected tangentially into said first reaction zone; said mixture is burned to form hot combustion gases for heat-

ing said feed; said feed is passed, initially surrounded by a helically moving annular blanket of said combustion gases, into said second reaction zone; said feed is heated by said combustion gases to a temperature in the range of 1500 to 3500° F. to cause same to react and form predominantly unsaturated hydrocarbons; the effluent from said second reaction zone is quenched in a quench zone to a temperature below reaction temperature; and said unsaturated hydrocarbons are recovered; the im-

10 provement comprising including at least 50 volume percent of aliphatic paraffin hydrocarbon in said feed; heating said feed in the preheating step to a temperature in the range of about 1000° to 1600° F. in admixture with steam in the range of 10 to 125 volume percent of the hydrocarbon feed so as to crack and convert a greater proportion of said paraffin-hydrocarbon to olefin hydrocarbon than would occur without said steam before passing the preheated feed and steam to said first reaction zone, whereby the amount of unsaturates in said effluent is increased and carbon deposition in said tube cracker, in said second reaction zone and in said quench zone is reduced.

2. The process of claim 1 wherein said feed comprises predominantly C₁ to C₄ paraffins.

3. The process of claim 1 wherein reaction conditions producing maximum yields of acetylene, including a temperature of at least 1900° F., are maintained and acetylene is recovered from the unsaturates.

30 4. The process of claim 3 wherein said feed consists essentially of C₁ to C₄ paraffins and the steam is in the range of 20 to 100 volume percent of the hydrocarbon feed.

5. The process of claim 4 wherein said feed comprises principally butane.

6. The process of claim 4 wherein said feed comprises principally propane.

7. The process of claim 1 wherein a mixture of steam and air in a volume ratio of steam to air in the range of 1:1 to 8:1 is preheated to an elevated temperature in the range of 800 to 1600° F. and injected with natural gas 55 as said combustible mixture, the O₂ in said combustible mixture being in the range of 70 to 90% of the theoretical amount for complete combustion of the fuel therein.

8. The process of claim 7 wherein reaction conditions producing maximum yields of acetylene, including a temperature of at least 1900° F., are maintained and acetylene is recovered from the unsaturates.

9. The process of claim 1 wherein reaction conditions producing maximum yields of ethylene, including a temperature in the range of 1500 to 1900° F., are maintained and ethylene is recovered from the unsaturates.
